UNITED STATES PATENT OFFICE.

WALTER HAHNEMANN, OF KITZEBERG, NEAR KIEL, GERMANY, ASSIGNOR TO SIGNAL
GESELLSCHAFT M. B. H., OF KIEL, GERMANY.

SUBMARINE SOUND-SIGNALING APPARATUS.

Application filed March 24, 1921. Serial No. 455,319.

(GRANTED UNDER THE PROVISIONS OF THE ACT OF MARCH 3, 1921, 41 STAT. L., 1313.)

The invention relates to that group of sound receivers in which the oscillatory system is composed of two independent oscillatory structures coupled to each other. 5 Such a system occurs, for example, when a microphone itself composed of mass parts and elastic members forming an oscillatory structure is connected with the sound diaphragm of such a receiver. For the operation of such apparatus the proper coupling of the two oscillatory structures with one another is of particular importance. This coupling is dependent on the constructional design of the two structures to be coupled, 10 that is, in the mentioned example, on the design of the sound diaphragm and in particular of the microphone. If, therefore, a different coupling (that is, a closer or looser coupling) is to be chosen than that which normally results in the case of a simple connection of two oscillatory structures of given size and design, it is necessary to alter the construction or design of at least one of the two oscillatory structures to be coupled. 15 Equally it is necessary, when one of the oscillatory structures is replaced by another of different dimensions, to alter the other of the two oscillatory structures because otherwise a different coupling would result than the one which has been found effective. Let it be assumed that in the course of time, a particular type of microphone has proved especially suitable, which microphone possesses when used with a 20 diaphragm of definite size a favourable degree of coupling. If now, for example, the size of the diaphragm must be altered because it is not strong enough, the relations of the tuning, etc., being otherwise the same, then on using the same tested microphone, with the diaphragm a different and less favourable degree of coupling is obtained. In order to again obtain the former 25 degree of coupling it is necessary to depart from the tested microphone construction and this departure necessitates a new series of experiments of uncertain length and uncertain result. 30 The present invention provides a means in such cases of again obtaining the desired favourable degree of coupling, of the oscillatory structures with respect to one another without altering the construction or design of the oscillatory structures them-

selves. It consists in connecting the oscillatory structures with one another by means of a lever mechanism of any suitable design. 35

The invention is represented in diagrammatic form in Figs. 1, 2 and 3. In all these figures, a diaphragm (the sound radiating member) is shown, which is secured at its periphery to a ring-shaped carrier or holder. This diaphragm forms part of one oscillatory structure of the coupled system. The second oscillatory structure comprises a 40 microphone. The relationship of the mass parts and the elastic members of the individual structures is as follows:

In the embodiment of the invention shown in Figure 1, the ring-shaped holder m_1 45 serves as the outer mass of one of the vibratory structures, which structure includes also the diaphragm e_1 and a portion of the mass m_2 . The diaphragm serves as the elastic member of this vibratory structure. 50 The diaphragm mass and certain other masses (namely, the mass of water, the fastening members of the microphone, and the like) fastened or considered to engage on the centre of the diaphragm, are considered 55 to be combined in the body or mass m_2 . This body or mass contains also parts which at the same time belong to the microphone, representing the second oscillatory structure. This is represented by the line l which 60 divides the body m_2 , by the letter r which designates the part belonging to the said second oscillatory structure (microphone), and by the letter s which designates the part 65 belonging to the first oscillatory structure (radiating diaphragm). The second oscillatory structure is formed by this portion r of the mass body m_2 , by the microphone diaphragm e_2 which serves as the elastic member, and by the other mass m_3 of the 70 microphone (casing or the like) supported on this microphone diaphragm. It is assumed that the degree of coupling effected 75 by joining the diaphragm and microphone together as shown in Fig. 1 has been found 80 particularly favourable. Now, if the size 85 of the diaphragm e_1 is for any reason whatsoever increased or diminished, as shown 90 in Figures 2 and 3 respectively, the absolute 95 amount of mass considered to be concentrated in the centre of the diaphragm at m_2 becomes altered if, as assumed, the tuning 100 relations are to remain the same. Such 105

- alteration, of course, causes the percentage r of the mass in m_2 belonging to the second oscillatory structure also to become altered and, since the degree of coupling between the two vibratory structures is determined by the relations of the masses m_3 to m_2 , and m_1 to m_2 , this alteration results in a change in the degree of coupling unless the microphone be altered correspondingly. Since 10 now it is desired that the microphone construction, and therefore the microphone mass r , remain constant, it is according to the present invention arranged to engage the diaphragm by means of a lever a adapted to transform or change the amplitudes of vibrations passing between the diaphragm and the microphone. It is possible according to the invention on adjusting the lever to secure the proper ratio of motion transformation, to again obtain the desired degree of coupling in the increasing (Fig. 2) or diminishing sense (Fig. 3) for every alteration of the radiating structure; because 20 the action of the mass s of the first oscillatory structure (the diaphragm) on the mass r of the second (the microphone) varies in direct proportion to the square of the lever transformation, according to the principle which forms the basis of the invention. 25
- The constructional design of the radiating member and the detecting apparatus in no way limits the scope of use of the invention. The inventive idea can be equally 30 advantageously used with radiating structures of any desired form, and detectors (microphones, telephones and the like) of any desired form. In particular the invention provides a new and easy way of fulfilling the well-known condition for the 35 efficient operation of such coupled systems in submarine sound receivers, according to which the ratio of the masses m_3 to m_2 must be equal to one or less than one. 40
- 45 The manner of construction of the lever system itself does not form the object of the invention, although it is naturally of importance that the lever should be preferably so constructed that its acoustic properties 50 are correct. In this connection it is desirable to avoid the use of ordinary pivots for the fulcrum of the lever. Instead of such pivots the lever itself may be reduced in cross-section at the fulcrum to such an extent as to enable it to bend at that point. The lever may also be reduced in cross-section at the point of attachment to the microphone to permit it to bend there. The reduced portions are indicated in Figures 2 55 and 3 at a_1 . At all other points the lever must be constructed substantially rigid with respect to the frequencies to be employed in the apparatus, and in its entire design should be preferably particularly light. Care should be taken in calculating such

constructions, that the masses of the levers themselves are included in the oscillatory masses, and secondly that the transformation ratio of the lever is calculated according to the above stated rule with this in 70 consideration. For example, the portion of the mass m_2 in Fig. 3 belonging to the microphone, and the masses of the lever itself (taking into consideration the amplitudes thereof), are included in the calculation of the composite mass which is used in comparison with the mass m_3 in determining the ratio of transformation required from the lever. 75

I claim:

1. In submarine sound receiving apparatus, two independently vibratory structures, and a lever coupling them together, the lever being so connected to the two vibratory structures as to transform the amplitudes of vibrations passing between said structures to an extent dependent upon the percentage of acoustic coupling to be created between the structures. 80

2. In submarine sound receiving apparatus, an independently vibratory sound radiating diaphragm, an independently vibratory sound detector, and a lever coupling them together, the lever being so connected to the diaphragm and detector as to transform the amplitudes of vibrations passing between the diaphragm and detector to an extent dependent upon the percentage of acoustic coupling to be created between them. 85

3. A sound receiving device comprising in combination; a primary vibratory structure including two vibratory masses connected by an elastic sound radiating member; a second vibratory structure in the form of a detector having a freely vibratable mass and a second vibratory mass; and a substantially rigid amplitude-transforming lever adapted to unite said second vibratory mass of the detector with a vibratory mass connected to the radiating member; the ratio of the free mass of the detector to the said united masses when the former is multiplied by the square of the ratio of transformation of the said lever, being at most equal to 1. 110

4. A sound receiving device comprising in combination; a primary vibratory structure including an elastic sound radiating diaphragm, a vibratory mass attached to the periphery of the diaphragm, and a vibratory mass at the center of the diaphragm; a second vibratory structure in the form of a detector having a freely vibratable mass and a second vibratory mass; and a substantially rigid amplitude-transforming lever adapted to unite said second vibratory mass with said vibratory mass at the center of the diaphragm; the ratio of said freely vibratable mass to said united masses when the former is multiplied by the square of the ratio of transfor-

mation of said lever, being at most equal to 1.

5. In sound signaling apparatus comprising a plurality of vibratory structures each including a plurality of masses connected by an elastic member, a lever having a point thereof of relatively small amplitude of motion connected to one structure and a point of relatively large amplitude of motion connected to another structure, the lever being arranged to transform the amplitudes of vibrations passing between the structures and to effect the degree of coupling between the structures.
- 10 6. In sound signaling apparatus comprising a plurality of vibratory structures each including a plurality of masses connected by an elastic member, a lever having a point thereof of relatively small amplitude of motion connected to a mass of one structure and a point of relatively large amplitude of motion connected to a mass of another structure.
- 15
- 20

ture, the lever being arranged to transform the amplitudes of vibrations passing between the structures and to effect the degree 25 of coupling between the structures.

7. In sound signaling apparatus comprising a plurality of vibratory structures each including a plurality of masses connected by an elastic member, a lever having a point 30 thereof of relatively small amplitude of motion connected to a mass of one structure and a point of relatively large amplitude of motion connected to a mass of another structure, the other mass of the last-named structure being freely vibratable, the masses connected by the lever forming a composite mass, and the square of the ratio of transformation of the lever multiplied by the 35 ratio of the freely vibratable mass to the 40 composite mass being at most equal to 1.

In testimony whereof I affix my signature.

WALTER HAHNEMANN.
